UNITED STATES PATENT OFFICE.

LUCIAN W. BUGBEE, OF INDIANAPOLIS, INDIANA, ASSIGNOR TO ONEPIECE BIFOCAL LENS COMPANY, OF INDIANAPOLIS, INDIANA, A CORPORATION.

MEANS FOR POLISHING MULTIFOCAL LENSES.

1,406,927.

Specification of Letters Patent. Patented Feb. 14, 1922.

Application filed March 22, 1920. Serial No. 367,754.

To all whom it may concern:

Be it known that I, LUCIAN W. BUGBEE, a citizen of the United States, and a resident of Indianapolis, county of Marion, and 5 State of Indiana, have invented a certain new and useful Means for Polishing Multifocal Lenses; and I do hereby declare that the following is a full, clear, and exact description thereof, reference being had to 10 the accompanying drawings, in which like numerals refer to like parts.

The object of this invention is the improvement of the polishing of surfaces of bifocal lenses or any lenses having a plurality of surfaces, and relates particularly to means for positively rotating a plurality of polishers which are held in place loosely by pins. In such polishing mechanism the lens holder is rotated and will, to some extent, cause rather uncertain and independent 15 rotary movement of the polishers, if not positively driven, which tends to cause differences in their action, whereas uniformity of polishing action by all of the polishing 20 buttons or means is desired.

This invention is an improvement over the construction set forth in my former application for Letters Patent Serial No. 365,400, filed March 13, 1920, wherein most of the 25 mechanism herein set forth is shown and described. In the construction in my former application, a belt extends around the two polishers or buttons so that the rotation of one polisher influences the rotation 30 of the other and tends to produce uniformity of rotation and action. The specific improvement herein over said former construction consists in an independent positively driven pulley and a belt extending around 35 said pulley and said plurality of polishers or buttons so that they will both positively rotate.

The full nature of the invention will be understood from the accompanying drawings and the following description and 40 claims:

In the drawings, Fig. 1 is a side elevation of a portion of a lens polishing machine including this invention. Fig. 2 is 45 a plan view of what is shown in Fig. 1. Fig. 3 is a vertical sectional view through parts of the machine showing the lens blank and holder in central vertical section, the remaining parts being in front elevation and 50 partially broken away. Fig. 4 is a plan

view of the lens, polishers and means for rotating the same that is shown in the other figures, the pin-carrying means and other mechanism being not shown. Fig. 5 is the same as Fig. 4 illustrating a modified form 60 where only the outer polisher is driven.

There is shown in Figs. 1 and 2 parts of a machine in connection with which this invention has been and can be used, although most parts of the machine are old. There 65 is shown a table 10 with a vertical shaft 11 mounted in the bearings 12, said shaft carrying a removable lens holder 13 of common type on which a target lens blank 14 is secured for treatment. The shaft 11 is driven 70 by means of a pulley 15 and belt 16. On said table there is a base plate 110 carrying stationary bearing posts 17 carrying bearings 18 in which bearing screws 19 are horizontally mounted, as shown in Fig. 2, 75 in connection with which the arm or frame 20 is pivoted at its rear end and its front end is acted upon by gravity for exerting pressure on the polishing means or buttons. The gravity can be increased by adding ad- 80ditional weights, not shown, as is often done in the practice.

In Fig. 3 there is shown a front elevation of the front end of the arm 20 which has a segmental-shaped plate 24 rigid therewith. The clamping plate 25 is associated with the plate 24 for clamping a rod 26 in proper position. Bolts 27 secure the plate 25 in position and one of those bolts extends through a slot 28 in the plate 24 so that the 85 angular position of the clamping plate 25 may be adjusted in order to hold the rod 26 in proper inclination.

The bifocal lens blank 14 as shown in Fig. 3 is secured on the lens holder 13 and 90 has a central area 30, which is the reading surface of the lens blank, and the surrounding annular area 31, which is the distance surface of the lens blank. These two surfaces appear in Fig. 4, and are there shown 100 separated by a division line 32, although in the actual lens said division line is practically invisible. For polishing the central or reading surface 30 a small button 35 is used and for polishing the surrounding surface 31 a larger button 36 is used. The small button has a diameter equal to one-half of the diameter of the reading surface 30 and the large polishing button has a diameter equal to the width of the distance 110

surface 31 between the edge of the blank and the reading surface. Said blank is what is known in the trade as a target lens bifocal blank. Said two surfaces have been 5 generated to give them the proper relative curvatures, prior to the polishing operation by the means herein set forth.

- The lens holder and lens are rotated and the polishing buttons 35 and 36 are held 10 in place by pins 37 and 38, respectively, arranged so as to permit the polishing buttons to revolve on the lens blank as they may be caused to revolve by the rotation of the blank. This usually gives sufficient revolution 15 of the buttons to cause the desired cross rubbing, as the buttons will rotate almost at the speed of the lens blank at its line of contact with the polishing button farthest from the center of the lens blank.
- 20 The pins 37 and 38 are secured in a bar 40 pivoted by a pin 41 to the lower end of the rod 26. This enables the bar 40 to rock and permit the polishing buttons to fully engage and accommodate themselves to the 25 surfaces of the blank during the polishing operation, and the weight of the arm 20, rod 26, bar 40 and pins 37 and 38 will be constantly exerted on the polishing buttons in order to cause the friction desired for the polishing 30 action.

In order to cause an equivalent polishing action by the two buttons, the bar 40 is provided with a number of holes 42 so that it can be properly pivoted to effect said result.

- 35 To this end the bearing pin 41 should be located at a point near the pin 38 of the larger button, for since the large button has two or three times the polishing surface of the small button, there should come to it 40 through the pin 38 proportionately more pressure. Therefore, the distances between the pivot 41 and the pins 37 and 38 should be substantially in reverse ratio to the diameters of the buttons.

- 45 Since the relative distances of travel on the lens blank of the outer and inner edges of the large button 36 are not relatively great, the outer portion of said button does not always rotate with the blank in the 50 direction of the arrow and it is desirable for that button to always rotate to effect cross polishing. Therefore, the two buttons or polishers are preferably rotated positively by a belt 50 operating in grooves 51 and 55 driven by a driving pulley 52 mounted on the upper end of a shaft 53 having bearings in the base plate 110 and a bearing arm 111 and driven by a pulley 54 and belt 55. This will cause both polishers or buttons to rotate 60 and to rotate in the same direction and in the direction in which the rotary movement of the blank tends to cause the small polisher or button to rotate.

In the modified form shown in Fig. 5, only the outer polisher or button 36 is rotated 65 positively by the belt 50 and in the direction shown. This is also a very satisfactory arrangement for it determines positively both the rotation and direction of rotation of said large button and it is of much less importance to positively drive the small button 70 than the large one, for the small button will always be rotated by the lens blank.

Since the blank under the outer edge of the small button travels infinitely faster than the portion under the inner edge of said button, which is at the center of the lens blank, the lens blank always causes the outer portion of the inner button to rotate in the same direction as the blank. If the pulley 52 is 75 adjusted as to its speed properly, in ratio to the speed of the lens blank holder, the two polishers or buttons in this last described arrangement can be caused to polish the different surfaces with a substantially uniform 80 effect.

The invention claimed is:

1. The combination with a lens holder for holding a plurality of concentric lens blank surfaces to be polished, and means for rotating the same, of a polishing button for each surface thereof, a pin frame having a pin for loosely engaging each button, vertically movable means to which said pin frame is pivoted between the pins so the pin frame can rock thereon vertically, and a single independently driven belt extending around all of said polishing buttons for positively rotating them simultaneously.

2. The combination with a rotary lens holder adapted to hold a lens blank having a central portion and a surrounding annular portion, of a polishing button for the surrounding annular portion with a diameter substantially the same as the width of said 100 surrounding portion, a polishing button for the inner portion having a diameter substantially one-half of said portion, a pin frame with a pin engaging each of said buttons and arranged so as to hold the button for the inner portion between the center and circumference of said portion and to hold the button for polishing the outer portion between the inner and outer peripheries of said portion and to hold said two buttons on opposite sides of the center of the central portion, vertically movable means to which said pin frame is pivoted between the pins so that it can rock vertically, and a single independently driven belt extending around 105 all of said polishing buttons for positively rotating them simultaneously.

In witness whereof, I have hereunto affixed my signature.

LUCIAN W. BUGBEE.
